ATTORNEY

UNITED STATES PATENT OFFICE

HANS BURMEISTER, OF BERLIN, GERMANY, ASSIGNOR TO PYRENE-MINIMAX CORPORATION, A CORPORATION OF DELAWARE

FOAM GENERATING APPARATUS

Application filed November 12, 1927. Serial No. 232,784.

The present invention relates to apparatus for producing foam for fire extinguishing purposes and has for an object to provide improved means for combining powder and water to form foam.

The nature and objects of the invention will be better understood from a description of a particular embodiment thereof, for the purposes of which description reference 10 should be had to the accompanying drawings forming a part hereof and in which—

Figure 1 is a central sectional view of a generator constructed in accordance with the principles of the invention,

15 Figure 2 is a cross-sectional detail view showing the arrangement of the adjustable spray device, and

20 Figure 3 is a central sectional view of an embodiment having a plurality of ejectors discharging into a mixing chamber.

The apparatus shown in Figs. 1 and 2 for the purposes of illustrating the invention has a suitable hopper 5 for carrying a charge of foam forming powder. The opening 6 in the 25 bottom of the hopper may conveniently be circular. In this opening is positioned a fitting 7 connected to a water inlet 8 and having a nozzle 9 cooperating with a suitable outlet 10 to form an ejector. Above the ejector a catch plate 11 serves to sufficiently close the opening 6 to support the charge of powder when dry in the hopper 5. This 30 plate also serves with the side walls 12 to provide a feeding chamber for the ejector. The outer edge of the catch plate 11 projects under the edge of the opening 6, a distance, 35 depending upon the angle of repose of the powder to be used, sufficient to prevent any substantial quantity of the powder from falling through to the feeding chamber, while dry.

A spray device 15 is arranged above the catch plate to direct a conical sheet of water into the mass of powder above the catch plate 45 to wash it down between the catch plate and the edge of the hopper opening, to the feed chamber when the device is in use. As shown, the ejector nozzle 9 and the spray device are supplied with water from the one 50 inlet 8. The spray device is preferably ad-

justable and, as shown, comprises an upper conical member 16 which is screw threaded into the cooperating member 17 and held in adjustable position by a set screw 18. Ordinarily it is so adjusted that approximately 55 one-sixth of the water supplied to the apparatus will pass through the spray device and over the catch plate. The sheet of water is directed downwardly toward and over the catch plate to wash the powder into the ejector feed chamber. A deflector plate 19 is supported above the edge of the catch plate and curved downwardly to deflect the stream of water or water and foam forming material downwardly, the distance between the 60 catch plate and the deflector being so adjusted as to reduce the churning effect around the edge of the catch plate and in the feed chamber as much as possible. Ordinarily it is more advantageous to position 65 the deflector plate relatively close to the catch plate as shown. Vents 20 lead from the upper part of the feeding chamber to the atmosphere to prevent, during operation, any substantial variation of pressure in this 70 portion of the device.

The apparatus shown in Fig. 3 is of the same general character as that shown in Fig. 1 but embodies a mixing chamber. As shown, the hopper 25 with an opening 26 in the bottom receives the charge of foam forming powder which is supported by a catch plate 27. A plurality of ejectors are formed by the nozzles 28 cooperating with suitable outlets 29 leading into the mixing chamber 30. Each 75 outlet is closed by a flap valve 31 arranged to open to permit flow of foam forming materials outward but to close in the event the back pressure in the mixing chamber exceeds the pressure within the ejectors. The foam 80 may be led from the mixing chamber through a suitable outlet 32 as by means of a hose.

It has been found that an ejector will under the same conditions draw in a liquid very 85 much more effectively than it will draw in a dry powder. In the described apparatus and process advantage is taken of this fact by converting the dry powder contained in the hopper into a relatively free flowing liquid slurry before subjecting it to the action of 90 100

the ejector. It is thus possible to feed into the water stream continuously a greater proportion of chemicals than could be supplied to the stream by an ejector operating upon dry powder. Moreover, the rate at which the chemicals are supplied in my apparatus and process depends upon the regulation of the sheet of spray that is used to wash the powder over the catch plate. By regulating this spray, it is possible to feed the chemicals at such rate as may be desired in proportion to the volume of the stream and thus to vary the quality of the foam produced to suit the requirements of the type of fire for which it is to be used.

The foregoing description is illustrative merely and is not intended as defining the limits of the invention.

I claim:

- 20 1. In apparatus for generating foam for fire extinguishing purposes, in combination, a hopper for foam forming powder having an opening in the bottom thereof, a catch plate beneath and close to said opening to sustain the powder therein and means for washing powder over the edge of said catch plate, substantially as and for the purpose described.
- 25 2. In apparatus for generating foam for fire extinguishing purposes, in combination, a hopper for foam forming powder having an opening in the bottom thereof, an ejector beneath said opening, a chamber beneath said opening serving as a feed chamber for said ejector, a catch plate beneath said opening and arranged to support a supply of dry powder in said hopper, a spray device arranged to direct a stream of water over said catch plate to wash powder into said feed chamber, a curved deflector plate extending over the edge of said catch plate and curved downwardly to deflect the water and material washed thereby downwardly, and a vent leading from the feed chamber, substantially as described.
- 30 3. In apparatus for generating foam for fire extinguishing purposes, in combination, a hopper for foam forming material having an opening in the bottom thereof, a catch plate beneath said opening, means for directing a stream of water over said catch plate to wash the foam forming material through said opening and a deflector plate adjacent the edge of said catch plate for determining the direction of flow of said stream, substantially as described.
- 35 4. The process of producing a continuous stream of fire extinguishing foam which comprises directing approximately one-sixth of a continuously flowing stream of water against the bottom of a bulk supply of foam producing chemicals to gradually wash the same from said supply, and drawing the slurry thus produced into the balance of said stream.
- 40 5. In apparatus for generating fire extinguishing foam a container for foam pro-

ducing powder, said container having a discharge opening, a member having a surface adjacent said opening, means for directing a continuous stream of water to wash the powder from said container against said surface, and means for forcing the slurry so formed into a continuously flowing stream of water.

6. In apparatus for generating fire extinguishing foam a container for foam producing powder, a chamber communicating with said container, means for directing a continuous stream of water to wash the powder into said chamber and thereby produce a slurry, means for directly introducing air into said chamber, and means for passing the slurry from said chamber into a continuously flowing stream of water.
